UNITED STATES PATENT OFFICE.

WILLIAM B. NIENKIRK, OF MAQUOKETA, IOWA.

APPARATUS FOR BURNING IN BEARINGS OF INTERNAL-COMBUSTION MOTORS.

Application filed September 14, 1922. Serial No. 588,240.

To all whom it may concern:

Be it known that I, WILLIAM B. NIENKIRK, a citizen of the United States, residing at Maquoketa, in the county of Jackson and State of Iowa, have invented new and useful Improvements in Apparatus for Burning in Bearings of Internal-Combustion Motors, of which the following is a specification.

10 In carrying out the present invention it is my purpose to provide an apparatus for burning in the bearings and running in oversize piston rings, etc., in order that the new bearings, pistons and piston rings will 15 be properly fitted so as to remain tight and not overheat when the motor is put into service after having been repaired or overhauled.

It is also my purpose to improve and simplify the general construction of the apparatus of the class described and to provide an apparatus whereby the crank shaft of the internal combustion engine and its associated parts will be operated at the proper 25 speed to facilitate the "wearing in" of such parts.

With the above recited objects in view and others of similar nature, the invention resides in the construction, combination and 30 arrangement of parts hereinafter set forth in and falling within the scope of the appended claims.

In the accompanying drawings:—

Figure 1 is a view in side elevation of my 35 apparatus the same being shown as connected to the crank shaft of an internal combustion motor.

Figure 2 is a top view of the same.

Figure 3 is a vertical sectional view on 40 the line 3—3 of Figure 1.

Figure 4 is a like view on the line 4—4 of Figure 1.

Figures 5 and 6 are views of details of the invention.

45 Referring now to the drawings in detail 1, 1 designate substantially A-shaped frames respectively, each comprising legs 2, 2 and a cross bar 3 and cross bars 4, and 5 respectively arranged above the cross bar 3 50 and in the same vertical plane as the latter. These frames 1, 1 are spaced apart in parallelism and are connected together by means of horizontal brace bars 6, and crossed brace bars 7 arranged at the opposite sides 55 of the frames and connected to the legs thereof as clearly shown in Figures 1 and 2

of the drawings. The lower ends of the legs 2 are formed of outstanding feet 8 that are bolted or otherwise connected to an appropriate foundation.

60 The cross bars 3, 4 and 5 on one frame lie respectively in the same horizontal plane as the cross bars on the other frame and journaled in the alining cross bars 3, 4 and 5 are horizontal shafts 9, 10 and 11, re- 65 spectively.

70 The lower shaft 9 carries upon one end a belt pulley 12 by means of which power may be transmitted to the shaft 9 in order to rotate the latter. The other end of the shaft 9 is equipped with a pinion 13 that meshes with a gear 14 fixed upon the shaft 10. Also fixed upon the shaft 10 adjacent to the gear 14 is a pinion 15 that meshes with a gear 16 fixed upon the shaft 11. In the present embodiment of my invention the gears 13 and 14 are in the ratio 1 to 4 while the pinion 15 and gear 16 are in a like ratio thereby stepping down the speed of the shaft 11.

75 One end of the shaft 11 is preferably squared in cross section as at 17 and projects beyond the bearing carried by the cross bar 5 and slidably mounted upon the squared end 17 of the shaft 11 is a sleeve 18. The outer end of the sleeve 18 is connected by 80 means of a universal joint 19 with one end of a short shaft 20 and the other end of a short shaft 20 is formed with a clutch collar 21 that is adapted to engage the cross pin 22 carried by the crank shaft of the motor. 85 In the present instance I have shown in Figure 6 of the drawings the fan belt pulley 23 that is on the forward end of the crank shaft of Ford motors which is illustrated in Figure 1 of the drawings.

90 In practice the belt pulley 12 is connected with a suitable source of power and motion transmitted to the shaft 9, pinion 13 and gear 14 to the shaft 10 and from the shaft 10 to the shaft 11 through the pinion 15 and gear 16. However, before power is applied to the belt pulley the motor "run in" 95 is arranged adjacent to the squared end of the shaft 11 and the shaft 20 connected to the crank shaft of such motor, 100 the universal joint 19 and the sleeve 18 permitting the shaft 11 to be connected to the crank shaft of the motor easily and quickly and irrespective of the distance between the motor and the shaft 11 within certain limits. The power being applied to 105 the belt pulley the shaft 11 permits the mo- 110

tion to the crank shaft of the motor to revolve such crank shaft at the proper speed thereby enabling the bearings, pistons, etc., to be properly "run in."

5 I have entered into a detailed description of the construction and relative arrangement of the parts embraced in the present and preferred embodiment of my invention, in order to impart a full, clear and exact understanding of the said embodiment. I do not desire, however, to be understood as confining myself to the specific construction and relative arrangement of parts inasmuch as in the future practice of the invention 10 various changes and modification may be made such as fall within the scope of the invention as defined in my appended claims.

Having described my invention, what I claim and desire to secure by Letters-Patent, is:—

1. In apparatus of the class described, the combination with A-shaped frames spaced apart in parallelism and each including legs and a cross bar and cross bars arranged above and in the same vertical plane as the first-mentioned cross bar, the cross bars of one frame being in the same horizontal planes as those of the other frame, shafts journaled in said alining cross bars respectively, means for transmitting power to the lowermost shaft, a step down gearing between the lowermost shaft and the next adjacent shaft and a step down gearing between the last-mentioned shaft and the top shaft and means whereby said top shaft may be connected to the crank shaft of an internal combustion motor substantially as and for the purpose described.

2. In apparatus of the class described, the combination with A-shaped frames

spaced apart in parallelism and each including legs and a cross bar and cross bars arranged above and in the same vertical plane as the first-mentioned cross bar, the cross bars of one frame being in the same horizontal planes as those of the other frame, shafts journaled in said alining cross bars respectively, means for transmitting power to the lowermost shaft, a step down gearing between the lowermost shaft and the next adjacent shaft and a step down gearing between the last-mentioned shaft and the top shaft, and adjustable means whereby said top shaft may be connected to the crank shaft of an internal combustion motor. 55

3. In apparatus of the class described, the combination with A-shaped frames spaced apart in parallelism and each including legs and a cross bar and cross bars arranged above and in the same vertical plane as the first-named cross bar, the cross bars of one frame being in the same horizontal planes as those of the other frame, shafts journaled in said alining cross bars respectively, means for transmitting power to the lowermost shaft, a step down gearing between the lowermost shaft and the next adjacent shaft and a step down gearing between the last-mentioned shaft and the top shaft, and adjustable means whereby said top shaft may be connected to the crank shaft of an internal combustion motor, said adjustable means comprising a sleeve slidably connected to said top shaft and designed to rotate therewith, a short shaft in line with said sleeve and designed to connect to the crank shaft of the motor at an universal joint between said short shaft and sleeve. 70

In testimony whereof I affix my signature.

WILLIAM B. NIENKIRK.
